Primary Examiner — Melanie H Tung(74) Attorney, Agent, or Firm — Ziegler IP Law Group, LLC(57) CLAIM

The ornamental design for a display screen or portion thereof with a graphical user interface, substantially as shown and described.

DESCRIPTION

The single FIGURE is a front view of a display screen or portion thereof with a graphical user interface.

The broken line showing a display screen or portion thereof, some of the text and graphic elements form no part of the claimed design.

1 Claim, 1 Drawing Sheet
